MEMO PAD HOLDER

Leo F. Wildgen, Minneapolis, Minn., assignor to Arthur Salm Inc., Chicago, Ill., a corporation of Illinois

Filed May 23, 1963, Ser. No. 75,035

Term of patent 14 years

(CL. D74—1)

FIG. 1 is a top plan view of a memo pad holder incorporating my new design;

FIG. 2 is a side elevational view thereof;

FIG. 3 is a top perspective view thereof as it appears with the flag in an extended position;

FIG. 4 is a front elevational view thereof; and

FIG. 5 is a front elevational view of the showing made in FIG. 1.

The dominant features of my design reside in the portions shown in full lines.

The back of my design is plain and unornamented.

I claim:

The ornamental design for a memo pad holder, substantially as shown and described.
